Primary Examiner—Nelson C. Holtje*Assistant Examiner*—Martha Thompson*Attorney, Agent, or Firm*—Notaro & Michalos**[57] CLAIM**

The ornamental design for a wrist watch, as shown and described.

DESCRIPTION

FIG. 1 is a top plan view of a wrist watch showing my new design therefor;

FIG. 2 is a bottom plan view thereof;

FIG. 3 is an upper end view thereof, the lower end being a mirror image;

FIG. 4 is a right side elevational view thereof;

FIG. 5 is a left side elevational view thereof;

FIG. 6 is a top plan view of a wrist watch showing a second embodiment of my design;

FIG. 7 is a bottom plan view of FIG. 6;

FIG. 8 is an upper end elevational view of FIG. 6, the lower end being a mirror image; and,

FIG. 9 is a right side elevational view of FIG. 6.

The left side elevational view of the embodiment of FIG. 6 is identical to FIG. 5.
